DISPENSER CAP FOR A PRESSURIZED CAN

Robert Podall, Highland Park, Ill., assignor to The Drackett Company, Cincinnati, Ohio, a corporation of Delaware

Filed Dec. 29, 1967, Ser. No. 9,985

Term of patent 14 years

(Cl. D9—258)

Fig.2.

Fig.3.

Fig.4.

Fig.1.

Fig.5.

FIG. 1 is a perspective view of a dispenser cap for a pressurized can showing my new design, the broken line showing of a pressurized can being for illustrative purposes only;

FIGURE 2 is a front elevational view thereof;

FIGURE 3 is a side elevational view thereof;

FIGURE 4 is a rear elevational view thereof;

FIGURE 5 is a top plan view.

I claim:

The ornamental design for a dispenser cap for a pressurized can, as shown and described.
